UNITED STATES PATENT OFFICE.

LAWRENCE F. MUSTEE, OF CLEVELAND, OHIO, ASSIGNOR TO JOSEPH H. MILLER.

TOWEL-FOLDING MACHINE.

Application filed October 21, 1922. Serial No. 596,064.

To all whom it may concern:

Be it known that I, LAWRENCE F. MUSTEE, a citizen of the United States, residing at Cleveland, in the county of Cuyahoga and 5 State of Ohio, have invented certain new and useful Improvements in Towel-Folding Machines, of which the following is a specification.

This invention relates to machines for 10 folding table-napkins, towels and other articles, and has for its main object to provide an automatic folding machine similar to that disclosed in Pat. No. 1,404,636 granted to me Jan. 24, 1922, but embodying certain 15 improvements in its design and operation.

In order that the invention will be clearly 20 understood, the same will be hereinafter fully described as illustrated in the accompanying drawings, and the novel features 25 thereof will be particularly pointed out in the appended claims.

Similar characters of reference are used in 30 the different views of the drawings to designate corresponding parts.

Figure 1 is a side elevation of a folding machine constructed in accordance with my invention, Fig. 2 is a plan view of the machine, half of the top thereof being broken away to better show the construction, Fig. 3 is a sectional elevation taken on line 4—4 of Fig. 4, Fig. 4 is a front end elevation of the machine, certain parts being broken away to better show the construction, Fig. 5 illustrates the valve actuating means for controlling the 35 suction to the suction-head 22, the valve being in its open position, Fig. 6 is a similar view, the valve having then closed, Fig. 7 illustrates the trip-members for operating said valve, Fig. 8 illustrates the valve actuating means for controlling the suction to the suction-head 73, the valve being in its closed position, Fig. 9 is a similar view, the valve being in its open position, Fig. 10 is an end view of Fig. 8 looking toward the 40 left, Fig. 11 illustrates the valve actuating mechanism for controlling the suction to the suction-head 113, the valve being in its open position, Fig. 12 is a similar view, the valve having been closed, Fig. 13 is an end view of Fig. 12, looking toward the right, Fig. 14 is a sectional view illustrating the pivotal and adjustable connection between the lever 129 and the rod 133, and Fig. 15 illustrates the means of pivotally connecting the pipe 122 to the suction tank 41.

Referring to the drawings, 1 and 2 rep-

resent the vertical sides and 3 the horizontal top of a suitable frame for the machine. The top 3 is open at 4 and supports a board 5 having a transverse slot at 6. From the 60 sides of the slot 6 depend spaced plates 7 and 8 forming a vertical guide for the first fold of the articles to be folded, and from the sides of the central space 9 of the rear plate 8 extend spaced plates 10 and 11 forming a longitudinal guide for the second fold of the articles to be folded. Forming a part of the frame of the machine are pairs of lower and upper longitudinal guide rails 12 and 13 for supporting pairs of roller-wheels 14—15 and 16—17 of carriages 18 and 19, which carry valve casings 20 and 21, connected by a tube 22 forming a suction-head. The tube 22 is provided at its lower 70 side with a slotted mouth 23 to which the articles to be folded are drawn, and bars 24 are arranged crosswise of said mouth to limit the entrance therein of the same. Said suction-head is moved longitudinally by 75 means of angular lever arms 25 and 26, which are fixed to the ends of a rock-shaft 27 rotatably supported in the sides of the frame, and having their upper slotted ends 28 and 29 engage rollers 30 and 31 on the projecting ends of a shaft 32 connecting 80 the carriages 18 and 19 and carrying the roller-wheels 14 and 16. The lever arms 25 and 26 are slotted at 33 and 34 for receiving rollers 35 and 36 of cranks 37 and 38, respectively, which cranks are fixed to the ends of 85 a power shaft 39 rotatably mounted in the sides of the frame and driven in any suitable manner as by a gear 40 fixed to said shaft. The valve casings 20 and 21 are connected with any suitable suction means, as 90 to a tank 41 to which is connected a pump 42, by tubes 43 and 44 having their upper ends bent inwardly and rotatably connected as at 45 to said valve casings while their other ends are slidably mounted within tubes 46 and 47 having their inwardly bent 95 lower ends rotatably connected to said tank. For controlling the suction through the valve casings 20 and 21 so that the suction 100 will act to draw articles to be folded against the mouth 23 when the suction-head is in the position shown, and cut off the suction when the suction-head is at the other limit of its movement, a valve as 48 is carried by an arm 49, which is fixed to a shaft 50 pivotally mounted in each of said valve casings. To the projecting end of the shaft 105 110

50 is fixed a cross-lever 51 having a roller 52 at the end of one of its arms, which is adapted to engage the downwardly curved surface 53 of a trip-member 54 and the upwardly curved surface 55 of a trip-member 56 for operating the valve. Said trip-members 54 and 56 are supported by longitudinally extending rods 57—58, which are fixed in upright brackets 59—60 of the frame 10 of the machine, and are adjustably fixed to said rods by means of set screws as at 61. To the other arm of said cross-lever 51 is pivoted at 62 a plunger rod 63 having its free end loosely mounted in the closed end 15 of a barrel 64, with a nut 65 upon said free end. Said barrel is pivoted as at 66 to the valve casing, and a suitable coiled spring 67 arranged in said barrel between a plunger 68 of said rod and the closed 20 end of the barrel tends to hold the valve either in its open or closed position. A finger 69 extends from the cross-lever 51 and is adapted to engage the stop lugs 70 and 71 projecting from the valve casing for limiting the movement of the valve.

A table-napkin, towel or other article to be folded, as designated by 72, is fed towards the transverse slot 6 of the top-board 5 in any suitable manner, until its 25 forward edge is under the slotted mouth 23 of the suction-head tube 22, when the same will be drawn thereto due to the valves 48 having been opened as the suction-head moves to that position by the striking of 30 the curved surface 53 of the trip member 54 by the roller 52. As the suction-head is moved in the opposite direction, the article 72 is carried thereby until its center is directly over the slot 6, at which moment 35 the roller 52 will strike the curved surface 55 of the trip member 56, thereby cutting off the suction by closing the valves 48 and allowing the article to fall.

For drawing the article 72, between the 40 transverse plates 7 and 8 for folding the same, as soon as said article falls from the suction-head 22, a vertically movable suction-head 73 is provided. This suction-head is fixed to a transverse bar 74, the ends of 45 which are slidably mounted upon vertical guide rods 75—76 carried by the frame of the machine, and is actuated by means of slot-levers 77 and 78 having one of their ends fixed to a transverse shaft 79 rotatably 50 mounted in the sides of the frame and their other downwardly extending ends as 80 pivoted to links as 81, which are pivoted between lugs at 82 projecting from the face of said bar. The levers 77 and 78 are actuated 55 by rollers at 83 of cranks as 84 engaging the sides of the slots thereof. Said cranks are fixed to a shaft 85, which is rotatably mounted in the frame of the machine and driven by any suitable means from the 60 power shaft 39 as gears indicated at 86.

The suction-head 73 is telescopically connected by a pipe 87 to a vertical tube 88 from which extends a branch 89 to a valve casing 90 connected by a pipe 91 to the tank 41. Suction from the tank 41 to the suction-head 73 is controlled by means of a valve 92 in the valve casing 90. Said valve is fixed to a shaft 93 rotatably mounted in the valve casing and having at one end an arm 94 carrying a roller 95, and at its other end an arm 96, to which is pivoted the plunger rod of a spring barrel 97, similar to the spring barrel 64, retaining said valve in its open or closed position. A suitably inclined cam 98, carried at the lower end of a bar 99 which is slidably mounted in a vertical guide 100 supported by the rear plate 8, is adapted to engage the roller 95 for closing the valve 92. The bar 99 is held in its upper position by means of a coiled spring 101 which is attached to a foot 102 extending therefrom and the frame of the machine, and is forced downwardly against the action of said spring by the transverse bar 74 engaging a bolt 103 carried by said foot. Said bolt is adjustably secured in the foot 102 to provide for changing the travel of the bar 99. The mechanism for opening the valve 92 consists of a link 104 pivoted to the roller arm 94 and to the arm of a bell-crank 105 which is pivotally supported upon the pipe 91, and a depending leg 106 having a bevelled shoulder 107 is pivoted to the other arm of said bell-crank. The leg 106 hangs vertically through the slotted free end 108 of an arm 109, the other end of which is fixed to the rock-shaft 27. The lower edge of the arm 109 is cut out at 110 to provide a nib 111 for engaging the shoulder 107 of said leg to force the leg downwardly to open said valve when the suction-head 73 is at the upper limit of its travel. Just before said suction-head reaches the downward limit of its travel, a member 112 carried by the arm 109, by engaging the forward edge of the leg, causes it to swing rearwardly so that its shoulder 107 will clear the nib 111 of the arm 109 to allow the cam 98 to close the valve.

At the moment the suction-head 73 is at the downward limit of its travel and the valve 92 is closed to cut off the suction thus releasing the article 72 being folded, a horizontally movable suction-head 113 is in position to draw said article between the before mentioned spaced plates 10 and 11 for its second folding. The suction-head 113 is supported by a transverse shaft 114, upon the ends of which are roller-wheels as 115 for traveling upon longitudinal track rods as indicated at 116 and having their ends fixed to the frame of the machine and the rear guide plate 8. From the suction-head 113 extends a branch 117 terminating in a laterally extending pipe 118, which is pivot-

ally connected at 119 to a valve casing 120. From the valve casing 120 extends a tube 121, which is slidably mounted in a pipe 122 having a transverse head 123, the ends of which are pivotally connected to the tank 41. The suction-head 113 is retained in the horizontal plane by a link 124 which is pivotally hung from a transverse shaft 125 supported upon roller-wheels as 126 for traveling upon the track rods 116, and in the lower end thereof is pivoted a pipe 118 extending laterally from the valve casing. Side bars as 127 serve to hold the shafts 114 and 125 in parallel relation. The suction-head 113 is reciprocated by means of the roller 83 of the crank 84 engaging the sides of the slots indicated by 128 of upright levers 129 and 130 having their lower ends pivoted as at 131 to the sides of the frame 20 of the machine, and having their upper ends pivotally connected at 132 with one end of rods as 133, the other ends of which rods are pivotally connected to the transverse shaft 114. The pivotal connection at 132 is formed by means of a block 134 provided with an opening for receiving the rod 133 and having a trunnion 135 which is pivoted in said lever. Nuts as 136 are threaded upon the rod at each side of the block 134 for adjusting the travel of the suction-head 113. In the valve casing 120 is a valve 137 fixed to a shaft 138 having arms at each end thereof, one of which carries a roller 139 while to the other is pivoted a spring barrel 140 for holding the valve in its open or closed position, all as previously described in connection with the valve casing 90. For opening the valve 137 to admit suction through the valve casing 120 when it is adjacent the rear guide plate 8, a bracket 141 is pivotally suspended from the shaft 114 for carrying a transverse pin 142 on one end of which is pivoted a push-bar 143 having a downwardly bent end 144 for engaging the roller 139, and on its other end a roller 145, which is adapted to be engaged by the lower bevelled edge 146 of a cam 147 at the upper end of the bar 99. The free end of the push-bar 143 is slidably supported in a hanger 148 depending from the shaft 125. For closing the valve 137 to cut off the suction and thus release the article after being folded, a trip-member 149 is fixed to the frame of the machine, and its rising rounding surface 150 is arranged in alignment with the travel of the roller 139.

Operation: The table-napkin, towel or other article to be folded as designated by 72, is fed towards the transverse slot 6 of the top-board 5 in any suitable manner and as its forward edge comes under the slot 23 of the suction-head 22, it is drawn thereto as the valves 48 are open, they having been opened by the rollers 52 striking the curved surfaces 53 of the trip-members 54 as said suction-head moves to the left. As the suction-head is moved in the opposite direction by the lever arms 25 and 26, the article 72 is carried thereby until its center is over the slot 6 of the top-board 5, and is dropped therefrom due to the rollers 52 striking the curved surfaces 55 of the trip-members 56 thereby closing the valves 48 and cutting off the suction to said suction-head. The article 72 is then drawn downwardly at its center between the plates 7 and 8, for folding it for the first time from end to end, by the suction-head 73, which was moved to its upper position by the lever arms 77 and 78 while the suction-head 22 was moving to the right. At the moment the suction-head 73 reached the upper limit of its movement, the valve 92 was opened by the arm 109 to cause suction, and as said suction-head is moved downwardly by said lever arms the article is carried thereby, until said suction-head reaches the downward limit of its movement and said valve is closed and the suction cut off by the inclined cam 98, which is moved downwardly by said suction-head, acting upon the roller 95. As the suction-head 73 moves downwardly, the suction-head 113 is moved to the left by the lever arms 129 and 130, and at the moment the suction-head 73 reaches the downward limit of its movement, the suction-head 113 is at the rear guide plate 8, and the valve 137 for the suction-head 113 is opened by the downward movement of the cam 147 to cause suction for drawing the article 72 between the plates 10 and 11 to make the second fold. When the suction-head 113 carrying the article 72 reaches the limit of its movement to the right, the valve 137 is closed by the roller 139 striking the curved surface 150 of the trip-member 149, thereby cutting off the suction and permitting the article 72, now folded for the second time, to fall from the suction-head.

From the drawings and description, it is readily seen that such a machine is capable of automatically folding table-napkins, towels and other materials, and it will be understood that slight changes in the details of construction may be made within the scope of the claims.

Having fully described my invention, what I claim is:

1. In a towel folding machine, the combination of a suction-head adapted to move horizontally, a suction-head adapted to move vertically, means for moving said suction-heads, the suction-heads being connected with suction means, valves for controlling the suction through said suction-heads, means for retaining the valves in their closed or open positions, means for opening said valves, and means for closing said valves, substantially as described.

2. In a towel folding machine, the combination of a transverse suction-head adapted to move horizontally, a transverse suction-head adapted to move vertically, a vertical suction-head adapted to move longitudinally, means for moving said suction-heads, the suction-heads being connected with suction means, valves for controlling the suction through said suction-heads, means for retaining the valves in their closed or open positions, means for opening said valves, and means for closing said valves, substantially as described.
3. In a towel folding machine, the combination of a suction-head adapted to move horizontally, a suction-head adapted to move vertically, means for moving said suction-heads, the suction-heads being connected with suction means, valves for controlling the suction through said suction-heads, means for retaining the valves in their closed or open positions, means for opening the valve of the first mentioned suction-head, means for closing the valve of the second mentioned suction-head when the valve of the first mentioned suction-head is opened, means for closing the valve of the first mentioned suction-head, and means for opening the valve of the second mentioned suction-head when the valve of the first mentioned suction-head is closed, substantially as described.
4. In a towel folding machine, the combination of a transverse suction-head adapted to move horizontally, a transverse suction-head adapted to move vertically, a vertical suction-head adapted to move longitudinally, means for moving said suction-heads, the suction-heads being connected with suction means, valves for controlling the suction through said suction-heads, means for retaining the valves in their closed or open positions, means for opening the valve of the first mentioned suction-head, means for closing the valve of the second mentioned suction-head when the valve of the first mentioned suction-head is opened, means for closing the valve of the first mentioned suction-head, means for opening the valve of the second mentioned suction-head when the valve of the first mentioned suction-head is closed, means for opening the valve of the third mentioned suction-head when the valve of the second mentioned suction-head is closed, and means for closing the valve of the third mentioned suction-head when the valve of the second mentioned suction-head is opened, substantially as described.
5. In a towel folding machine, the combination of a suction-head adapted to move horizontally, a suction-head adapted to move vertically, means for moving said suction-heads, the suction-heads being connected with suction means, valves for controlling the suc-

tion through said suction-heads, the valves being fixed to pivotally supported shafts, arms extending from the shaft of the valve of the first mentioned suction-head, means connected to one of the arms for retaining the valve in its closed or open position, means adapted to be engaged by the other arm for closing or opening the valve, and means for causing the opening and closing of the valve of the second mentioned suction-head upon the closing and opening of the valve of the first mentioned suction-head, substantially as described.

6. In a towel folding machine, the combination of a suction-head adapted to move horizontally, a suction-head adapted to move vertically, means for moving said suction-heads, the suction-heads being connected with suction means, valves for controlling the suction through said suction-heads, the valves being fixed to pivotally supported shafts, arms extending from the shaft of the valve of the first mentioned suction-head, a pivotally supported barrel, a plunger rod slidably mounted in the barrel, a spring tending to hold the plunger rod in its outer position, the plunger rod being pivoted to one of said arms for retaining the valve in its closed or open position, trip-members adapted to be engaged by the other arm for closing or opening the valve, and means for causing the opening and closing of the valve of the second mentioned suction-head upon the closing and opening of the valve of the first mentioned suction-head, substantially as described.

7. In a towel folding machine, the combination of a suction-head adapted to move horizontally, a suction-head adapted to move vertically, means for moving said suction-heads, the suction-heads being connected with suction means, valves for controlling the suction through said suction-heads, means for retaining the valve of the first mentioned suction-head in its closed or open position, means for opening said valve, means for closing said valve, the valve of the second mentioned suction-head being fixed to a pivotally supported shaft, arms extending from the shaft, a pivotally supported barrel, a plunger rod slidably mounted in the barrel, a spring tending to hold the plunger rod in its outer position, the plunger rod being pivoted to one of said arms for retaining the valve in its closed or open position, means for actuating the other arm to open the valve upon the closing of the valve of the first mentioned suction-head, and means for actuating said other arm to close the valve upon the opening of the valve of the first mentioned suction-head, substantially as described.

8. In a towel folding machine, the combination of a suction-head adapted to move horizontally, a suction-head adapted to move vertically, means for moving said suction-heads, the suction-heads being connected with suction means, valves for controlling the suc-

- vertically, means for moving said suction-heads, the suction-heads being connected with suction means, valves for controlling the suction through said suction-heads, 5 means for retaining the valve of the first mentioned suction-head in its closed or open position, means for opening said valve, means for closing said valve, the valve of the second mentioned suction-head being fixed 70 to a pivotally supported shaft, arms extending from the shaft, a pivotally supported barrel, a plunger rod slidably mounted in the barrel, a spring tending to hold the plunger rod in its outer position, the plunger rod being pivoted to one of said arms for retaining the valve in its closed or open position, means including a pivotally supported leg for actuating the other arm to close the valve, means for forcing the leg in one 75 direction to open the valve upon the closing of the valve of the first mentioned suction-head, and means for actuating said other arm to close the valve upon the opening of the valve of the first mentioned suction-head, 80 substantially as described.
9. In a towel folding machine, the combination of a suction-head adapted to move horizontally, a suction-head adapted to move vertically, means for moving said suction-heads, the suction-heads being connected by suction means, valves for controlling the suction through said suction-heads, means for retaining the valve of the first mentioned suction-head in its closed or open position, 85 means for opening said valve, means for closing said valve, the valve of the second mentioned suction-head being fixed to a pivotally supported shaft, arms extending from the shaft, a pivotally supported barrel, a plunger rod slidably mounted in the barrel, a spring tending to hold the plunger rod in its outer position, the plunger rod being pivoted to one of said arms for retaining the valve in its closed or open position, means including a pivotally supported leg for actuating the other arm to close the valve, the leg having a shoulder, a lever arm adapted to engage the shoulder for forcing the leg in one 90 direction to open the valve upon the closing of the valve of the first mentioned suction-head, means carried by the lever arm for pushing the leg out of engagement with the lever arm, and a cam for engaging said other arm to actuate it for closing the valve upon the opening of the valve of the first mentioned suction-head, substantially as described.
10. In a towel folding machine, the combination of a suction-head adapted to move horizontally, a suction-head adapted to move vertically, means for moving said suction-heads, the suction-heads being connected with suction means, valves for controlling the suction through said suction-heads, means for retaining the valves in 95 their closed or open positions, means for opening the valve of the first mentioned suction-head, means for closing the valve of the second mentioned suction-head when the valve of the first mentioned suction-head is opened, means for closing the valve of the first mentioned suction-head, means for opening the valve of the second mentioned suction-head when the valve of the first mentioned suction-head is closed, the valve of the third mentioned suction-head being fixed to a rotatably mounted shaft, arms extending from the shaft, means connected to one of the arms for retaining the valve in its closed or open position, a cam for actuating the other arm for opening the valve upon the closing of the valve of the second mentioned suction-head, and a trip-member adapted to be engaged by said other arm for closing the valve upon the opening of the valve of the second mentioned suction-head, substantially as described.
11. In a towel folding machine, the combination of a suction-head adapted to move horizontally, a suction-head adapted to move vertically, means for moving said suction-heads, the suction-heads being connected with suction means, valves for controlling the suction through said suction-heads, means for retaining the valves in 100 their closed or open positions, means for opening the valve of the first mentioned suction-head, means for closing the valve of the second mentioned suction-head when the valve of the first mentioned suction-head is opened, means for closing the valve of the first mentioned suction-head, means for opening the valve of the second mentioned suction-head when the valve of the first mentioned suction-head is closed, the valve of the third mentioned suction-head being fixed to a rotatably mounted shaft, arms extending from the shaft, means connected to one of the arms for retaining the valve in its closed or open position, a push-bar adapted to engage the other of said arms for opening the valve, a cam for actuating the push-bar to open the valve upon the closing of the valve of the second mentioned suction-head, and a trip-member adapted to be engaged by said other arm for closing the valve upon the opening of the valve of the second mentioned suction-head, substantially as described.
12. In a towel folding machine, the combination of a suction-head adapted to move horizontally, a suction-head adapted to move vertically, means for moving said suction-heads, the suction-heads being connected with suction means, valves for controlling the suction through said suction-heads, the valves being fixed to pivotally supported shafts, arms extending from the shaft of the first mentioned suction-head, means connected to one of the arms for retaining the valves in 105 110 115 120 125 130

valve in its closed or open position, means adapted to be engaged by the other arm for closing or opening the valve, the last mentioned means being adjustable for setting at various positions, and means for causing the opening and closing of the valve of the second mentioned suction-head upon the closing and opening of the valve of the first mentioned suction-head, substantially as described.

13. In a towel folding machine, the combination of a suction-head adapted to move horizontally, means for moving the suction-head, the suction-head being connected with suction means, a valve for controlling the suction through the suction-head, means for opening said valve, means for closing said valve, and adjustable means whereby the time said means opens and closes said valve may be changed, substantially as described.

14. In a towel folding machine, the combination of a movable suction-head, means for moving the suction-head, the suction-

head being connected with suction means, a valve for controlling the suction through the suction-head, the valve being carried by the suction-head, and means whereby said valve will be opened at the beginning of the movement of the suction-head and closed at the end of the movement of the suction-head, substantially as described.

15. In a towel folding machine, the combination of a movable suction-head, means for moving the suction-head, the suction-head being connected with suction means, a valve for controlling the suction through the suction-head, the valve being fixed to a shaft pivotally supported in the suction-head, an arm extending from the shaft, means adapted to be engaged by the arm at the beginning of the movement of the suction-head for opening the valve and at the end of the movement of the suction-head for closing said valve, substantially as described.

In testimony whereof I affix my signature.

LAWRENCE F. MUSTEE.
